UNITED STATES PATENT OFFICE.

JOHN L. RIGGAN, OF SPRING GROVE, VIRGINIA.

CRANK-HANDLE-RETAINING DEVICE.

1,271,774.

Specification of Letters Patent.

Patented July 9, 1918.

Application filed November 13, 1916. Serial No. 131,092.

To all whom it may concern:

Be it known that I, JOHN L. RIGGAN, a citizen of the United States, residing at Spring Grove, in the county of Surry and 5 State of Virginia, have invented certain new and useful Improvements in Crank-Handle-Retaining Devices, of which the following is a specification.

The present invention has reference generally, to improvements in retaining devices and more particularly relates to a crank handle retaining device.

The invention has for its primary aim and object to provide novel supporting means 15 for the crank retaining arm whereby to hold the arm in an inoperative position to permit of the use of the crank and to also maintain the retaining arm in engagement with the crank to consequently support the 20 crank in an upright position, thus preventing mud, etc., from engaging the crank when the motor vehicle to which it is connected, is in operation.

More particularly, the present invention 25 embraces the provision of novel brackets constructed to support the registry number plate and to rotatably support and co-act with the spring retaining arm so as to consequently maintain the latter in either of its 30 adjusted positions.

Among the other aims and objects of the present invention may be recited the provision of a device of the character mentioned with a view to compactness, and in which 35 the number of parts are few, the construction simple, the cost of production low, and the efficiency high.

Other improvements and novel details in the construction and arrangement of parts 40 will be appreciated from the detailed description below, which is to be read in connection with the accompanying drawings forming a part herein, and wherein I disclose a preferred embodiment of the invention 45 for the purpose of illustration.

The preferred embodiment of my invention is clearly illustrated in the accompanying drawings, in which:—

Figure 1 is a front elevation of my invention applied to a motor vehicle and posi-

tioned so as to support the crank in an upright position.

Fig. 2 is a transverse section taken on line 2—2 of Fig. 1 in the direction in which the arrow points, the other parts being shown 55 in elevation.

Fig. 3 is a top plan of my invention.

Fig. 4 is an enlarged perspective detail of one of the improved brackets.

Similar characters of reference are employed in all of the above described views to indicate corresponding parts.

Referring now, more particularly, to the accompanying drawings I have arranged the front end of the chassis 1 in a supported 65 position on the front chassis supporting spring 2 and in supporting the radiator 3 with respect to the front end chassis 1 I provide a support 4 which rests on the front end of the chassis as indicated in Fig. 1 and 70 which is provided with an opening in which is journaled a driving shaft 5 of the vehicle. A crank 6 is operatively connected to the projecting end of the shaft 5. It is to be noted that the support has laterally projecting 75 ears 7 extending in opposite directions from the respective sides of the support and adjacent the respective ends thereof in which are arranged the ends of U-bolts 8, the latter being first straddled about the 80 front end of the chassis 1 and the spring 2 as indicated in the drawings while the free projecting ends are engaged by nuts 9, to maintain the parts in the position described.

Now, in order to provide the improved 85 supporting means for the retaining means, heretofore mentioned, I have provided my improved brackets generally indicated by the numeral 10. In the present instance each of these brackets is preferably formed 90 from a single blank of sheet metal or else cast in an integral piece and embodies a body portion 11 having an opening 12 therein, one end of the body being bent to provide an upstanding arm 13 in which is formed an 95 opening 14 for a purpose to be described. The upper end of the arm is bent outwardly at right angles to provide a flange 15 while the outer edge of the flange is beveled to provide a guide 16 also for a purpose to be de- 100

scribed. The opposite end of the body is offset to consequently provide an arm 17 having a horizontal slot 18 therein, the offset portion being also bent as indicated by the numeral 19 5 so as to arrange the arm 18 in a plane at right angles to the plane of the body portion 11. In connecting the supporting brackets of which there is a pair, the openings of the securing portion are arranged about the upper 10 ends of the outer portions of the U-shaped bolts preparatory to the application of the nuts 9 and are clamped in a substantially rigid position with respect to the support 4 by means of the nuts. It is to be noted that the arms 17 of the brackets extend outwardly in opposite directions to each other when applied and are also arranged in a plane in advance of the plane of the outer portions of the U-shaped bolts 8 as will be 15 apparent upon reference to Fig. 2, this arrangement permitting of the application of the registry plate on the arms as indicated by the dotted lines in Fig. 2.

With a view toward providing suitable means for removably retaining the crank arm 6 in an upright position where it will not be engaged by mud, etc., while the motor vehicle is in operation, I have provided my improved retaining arm which is constructed from a single piece of resilient wire bent upon itself to provide legs 20. The outer ends of the legs are bent outwardly in opposite directions to provide feet 21 which are journaled in the openings 14 and the arms 30 35 13 of the brackets. The intermediate or bridge portion of the retaining arm is also bent inwardly in a U-shape form to provide a recess 22 to permit of the arm being straddled about the crank 6 to consequently retain the same in an upright position.

The operation of the invention may be reviewed as follows:—

Normally, the legs 20 of the retaining arm are held outwardly so that the recess 22 engages the crank 6, this being caused by the beveled surface or guides 16. When it is desired to crank the machine the retaining arm is lifted upwardly and moved inwardly 45 50 55 so that the legs 20 ride upon the guides 16 and finally engage the opposed straight edges on the flanges 15 where, because of the inherent resiliency of the retaining arm, the legs are maintained in a position as indicated by dotted lines in Fig. 2. After the machine is started, the crank is arranged in a vertical position and it is only necessary to pull the retaining arm outwardly and as soon as it strikes the beveled guide 16 it will 60 65 automatically spring outwardly so that the recess will receive the crank 6 and its walls tightly engaged against the crank to hold it at all times from rattling.

As many changes could be made in the above construction and many apparently

widely different embodiments of this invention could be made without departing from the scope thereof, it is intended that all matter shown in the accompanying drawings shall be interpreted as illustrative and not 70 in a limiting sense. It is also to be understood that the language used in the following claims is intended to cover all of the generic and specific features of the invention herein described and all statements of the 75 scope of the invention, which, as a matter of language, might be said to fall therebetween.

Having described my invention, what I claim as new and desire to secure by Letters Patent is:—

1. An automobile crank handle retaining device, which comprises a pair of brackets formed of flat material, each bracket having a body portion adapted to be secured to the automobile, with flanges extending therefrom, one of said flanges extending vertically with a hole therein, and having one end of the flange bent to lie in the same plane as the body portion, said end being provided with an angularly cut outer corner, 90 and a spring having its ends bent to form shafts so that the spring is adapted to be rotatably secured in the holes in vertical flanges, and to coöperate with the bent ends of said flanges, said spring being positioned 95 therebetween to expand against the vertical flanges and adapted to engage with the crank handle.

2. A device of the character described, which comprises a pair of rigidly mounted 100 spaced brackets having flanges thereon, an inherently resilient crank retaining arm pivotally mounted in the brackets and coöperating with the flanges so as to be held in an operative or an inoperative position, and 105 the outer corners of the opposed flanges being beveled to facilitate movement of the retaining arm into its operative and inoperative positions, and when in an operative position, the resilient arm engages with the 110 underside of each of the brackets.

3. A device of the character described, which comprises a pair of brackets each one of which is formed of a single piece of material and consists of a body portion, an upright arm, and an angularly projecting flange projecting from said arm, said flange having a beveled outer corner, and a resilient crank retaining arm pivotally mounted in the upright portions of the bracket. 115 120

4. An auto crank handle retaining device which comprises a pair of rigidly mounted brackets having securing portions, upright arms and inwardly projecting flanges, the upper corners of said flanges being beveled, 125 a retaining arm formed from a single piece of metal bent to have an approximately W-shape, the legs of which are pivotally mounted in the arms of the brackets, the intermediate portion of the retaining arm being 130

adapted to engage with the crank, the legs of the retaining arm coöperating with the flanges so as to be maintained in the inoperative and operative positions, and the bevelled outer corner of the flanges facilitating the movement of the retaining arm to either of its adjusted positions.

In testimony whereof I affix my signature in presence of two witnesses.

JOHN L. RIGGAN.
